UNITED STATES PATENT OFFICE.

IRA J. OWEN, OF GRAND RAPIDS, MICHIGAN, ASSIGNOR, BY MESNE ASSIGNMENTS,
TO BISSELL CARPET SWEEPER CO., OF GRAND RAPIDS, MICHIGAN, A CORPORATION
OF MICHIGAN.

PORTABLE ELECTRIC SUCTION CARPET SWEEPER AND CLEANER.

Application filed April 17, 1922. Serial No. 553,966.

To all whom it may concern:

Be it known that I, IRA J. OWEN, a citizen of the United States, residing at Grand Rapids, county of Kent, State of Michigan, have invented certain new and useful Improvements in Portable Electric Suction Carpet Sweepers and Cleaners, of which the following is a specification.

This invention relates to improvements in portable electric suction carpet sweepers and cleaners. It relates particularly to the electric means and mechanism.

The main objects of the invention are:

First, to provide in such a cleaner a compact, efficient, and flexible electrical mechanism and wiring system.

Second, to provide such a structure that is effectively housed and protected and which is safe from all standpoints.

Further objects, and objects relating to details and economies of construction and operation will definitely appear from the detailed description to follow.

The objects of the invention are accomplished by the devices and means described in the following specification. The invention is clearly defined and pointed out in the claims.

A structure which is a preferred embodiment of the invention is fully illustrated in the accompanying drawing, forming a part of this application, in which:

Fig. I is a detail longitudinal sectional side elevation view on a line corresponding to line 1—1 of Fig. II, of a combination carpet sweeper and suction cleaner embodying the features of the invention, the shell of the motor housing appearing mainly in full lines and the handle being broken away.

Fig. II is an enlarged detail plan view of the motor casing base and lower end of the handle connection, the cover being removed, and showing in dotted line diagrammatically the electrical circuits and connections.

Fig. III is a side elevation view of the complete handle structure broken into sections and the pivotal connection thereof to the motor casing base.

Fig. IV is an enlarged detail vertical longitudinal sectional view through the central portion of the handle grip and cross-shift switch mechanism, portions being shown in full lines for the sake of clearness.

Fig. V is an enlarged detail transverse sectional view taken on line 5—5 of Fig. IV, 55 showing details of the socket.

Fig. VI is an enlarged detail sectional view on the irregular inclined line 6—6 of Figs. I and III, showing the wiring and contact connections and insulations along with 60 the pivotal handle connection.

Fig. VII is an enlarged detail sectional view through the pivotal joint at one side of the bifurcated handle taken on the same line 6—6 of Fig. I, being a complete detail 65 of the pivotal connection and electrical contacts at one side.

In the drawing similar numerals of reference refer to similar parts throughout the several views and the sectional views are 70 taken looking in the direction of the little arrows at the ends of the section lines.

The parts of the drawing will be considered by their numbers.

1 is the main case of an electric suction 75 sweeper having a combination suction and sweeper nozzle 2, an electric motor 3 on motor base 3', and a suction fan 4. A rotary carpet sweeper brush 5, indicated by dotted lines in Fig. I, is driven by the propeller shaft 7 through suitable connections to the friction gear 8.

The collected dust and dirt is delivered through the discharge nozzle 9 to any suitable bag or collector, not shown. 85

The electric motor 3 is of the vertical type and is disposed on a suitable base 10 and is completely housed by the casing cover 10'. The electric motor is of any suitable type for the purpose. These parts are especially 90 formed so that the electric motor and the base are readily accessible by removing the cover 10' and detaching the base 10. To this end the base 10 is provided with laterally projecting ears 11, 11 which are recessed and provided with insulator plugs 12 within the recess. The handle 13 is bifurcated or forked at 14, the prongs of the fork terminating in suitable bosses 15 which contain insulating plugs 16. A horizontal pivot 100 bolt 17 connects each of the ears 11 with its corresponding boss 15.

Between each pair of insulating plugs 12 and 16 are interposed electric contacts 12' and 16', annular in form, whereby the handle can be readily raised and lowered and 105

turned on its pivot without flexing and bending the electric wiring and without any danger of breaking the circuit.

A pair of wires 18, 19 are connected to 5 the manually controlled cross plug switch 20 interposed in proximity to the hand hold or grip 21 of the handle. The cross pin 22 of the switch is disposed in the central vertical plane at that point for convenience of 10 operation.

An electric socket 23 is provided at the end of the horizontal hand hold or grip to receive electric plug 24 which has a flexible contact tube 25 connected thereto to prevent undue flexing and breaking of the electric cord 26, which is preferably of the usual lamp cord construction. This machine is designed to connect to an electric lamp socket.

20 Disposed between the ears 11, 11 is a segment bracket 27 containing a series of perforations in the central vertical plane. A spring plunger bolt 28 very similar to a window stop is disposed in supporting insulation block 29 in the lower end of the handle 13. It is acted upon by spring 30 and cooperates with the perforated segment 27 and serves to adjust the handle and lock the same in any position required and permits ready release. A rod 31 is connected to the bolt and is curved outwardly through a slot 31' in the side of the handle and terminates in a knob or finger piece 32 by which the bolt is manipulated and adjusted. 35 This slot 31' is notched so that the bolt may be withdrawn and disengaged while the machine is being used.

Electric conductors or wires 33, 34 lead to and from the contacts 12' to the motor of 40 any suitable design, as indicated in Fig. II, one wire being the lead and the other the return. An electric fuse 35 is provided in the circuit on the motor frame inside the casing.

45 The forks 14 of the handle are hollow and electric conductors 36, 36 lead to and from the contacts 16' to insulated binding screws 37 where electric conductors 38 are attached to the wires 18 and 19 within the hollow handle. Spring contact terminals 18' and 50 19' are provided for conductors 18 and 19 and are disposed upon insulation plug block 29. The lower end of the handle is clamped in the socket by ring nut 13' and can be 55 readily detached.

From this it will be seen that the electric connections here are entirely contained within the tubular parts or within the casing of the machine and are not exposed to friction or wear. The electric cord 60 26 is protected against friction at the outer end of the handle. Locking means are provided for holding the handle in elevated position when not in use and so that the 65 handle may be released when the machine is

in operation, permitting the utmost freedom of manipulation and the perfect supporting of the parts when not in use so that they are the better protected from injury.

The handle fork herein can, of course, be 70 extended and embrace the sides of the casing in place of the rearwardly projecting lugs without materially changing the structure and I have not deemed it necessary to illustrate the same. Also, as to the electrical 75 connections at the end of the handle, the socket parts may be reversed without departing from my invention. This is sometimes desirable, especially where high voltages are used. The exposed socket plug is 80 distinguished from the socket, sometimes exposing the user to shock.

Electric connections of various kinds have been provided in such relation and it is not the purpose of this patent to claim such 85 electric connections broadly, but it is desired to claim the particular arrangement illustrated in its particular form and also to claim the various features thereof broadly as pointed out in the appended claims. 90

Having thus described the invention, what is claimed as new and desired to secure by Letters Patent, is:

1. In an electric suction cleaner, the combination of a suitable motor and casing, a hollow handle with detachable hollow forks at its lower end with a hand grip portion above, electric connections disposed within the hollow handle and extended into said hollow bifurcations, suitable ears on the 100 motor casing, insulator blocks interposed between the said ears and the said handle, annular contact devices thereon, and connections therefor from the conductors within the handle to the motor within the casing, 105 coacting as specified.

2. In an electric suction cleaner, the combination of a suitable motor and casing, a hollow handle, electric connections disposed within the hollow handle, a suitable ear on 110 the motor casing, insulator blocks interposed between the said ear and the said handle, annular contact devices thereon, and connections therefor from the conductor within the handle to the motor within the casing, 115 coacting as specified.

3. In an electric suction cleaner, the combination with the casing, a detachable base portion for the motor on the said casing, a hollow handle pivotally connected to the 120 said motor base, electric connections disposed within the hollow handle, connections from the conductor within the handle to the motor upon the base whereby the handle and electric connections and motor are a 125 separable unitary structure in the said suction cleaner.

In witness whereof, I have hereunto set my hand and seal.

IRA J. OWEN. [L. S.]
